225,100

BOTTLE OR SIMILAR ARTICLE

Gerhard Wiedmann, Lochacker, Switzerland, assignor to Greiner Electronic AG, Langenthal, Switzerland

Filed Mar. 22, 1971, Ser. No. 127,069

Term of patent 14 years

Int. Cl. D9—01

U.S. Cl. D9—18

FIG. 1 is an elevational view of a bottle or similar article showing my new design;

FIG. 2 is an elevational view looking from the right of FIG. 1;

FIG. 3 is an elevational view showing the side opposite that seen in FIG. 1;

FIG. 4 is a top plan view;

FIG. 5 is a bottom plan view;

FIG. 6 is a sectional view taken on the line 6-6 of FIG. 1;

FIG. 7 is a fragmentary sectional view taken on the line 7-7 of FIG. 1;

FIG. 8 is an elevational view of another embodiment of my new design;

FIG. 9 is an elevational view looking from the right of FIG. 8;

FIG. 10 is an elevational view showing the side opposite that seen in FIG. 8;

FIG. 11 is a top plan view;

FIG. 12 is a bottom plan;

FIG. 13 is a sectional view taken on the line 13-13 of FIG. 8; and

FIG. 14 is a fragmentary sectional view taken on the line 14-14 of FIG. 8.

I claim:

The ornamental design for a bottle or similar article, as shown and described.
